(57) **CLAIM**

The ornamental design for a radiator grille with light for an off-road vehicle, as shown and described.

DESCRIPTION

FIG. 1 is a perspective view of a radiator grille with light for an off-road vehicle, showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side view thereof; and,

FIG. 7 is a right side view thereof.

The broken line portions of the radiator grille are for illustrative and environmental purposes that form no part of the claimed design.

1 Claim, 2 Drawing Sheets
